Primary Examiner — Cynthia Ramirez*Assistant Examiner* — Michael A Maharajh(74) *Attorney, Agent, or Firm* — Young Basile Hanlon & MacFarlane, P.C.(57) **CLAIM**

The ornamental design for a trigger point therapy device, as shown and described.

DESCRIPTION

FIG. 1 is a perspective view of a trigger point therapy device.

FIG. 2 is a front side view of the trigger point therapy device of FIG. 1, the rear side view, the left side view, and the right side view being the same as the front side view.

FIG. 3 is a top view of the trigger point therapy device of FIG. 1; and,

FIG. 4 is a bottom view of the trigger point therapy device of FIG. 1.

The broken lines in the drawings are for the purposes of illustrating portions of the trigger point therapy device that form no part of the claimed designed. The trigger point therapy device is shown with a symbolic break in its length. The appearance of any portion between the break lines forms no part of the claimed design.
